UNITED STATES PATENT OFFICE.

EDWARD A. RIX, OF SAN FRANCISCO, CALIFORNIA.

RECIPROCATING ENGINE.

No. 862,107.

Specification of Letters Patent.

Patented July 30, 1907.

Original application filed August 16, 1905, Serial No. 274,487. Divided and this application filed December 16, 1905.
Serial No. 292,074.

To all whom it may concern:

Be it known that I, EDWARD A. RIX, a citizen of the United States, residing at San Francisco, county of San Francisco, and State of California, have invented new and useful Improvements in Reciprocating Engines, of which the following is a specification.

My invention relates to reciprocating engines and particularly to that class of such engines employed in conjunction with rock drills; the object of the invention being to produce a valve motion to actuate the engine piston and rock drill in such a manner as to eliminate defects which have heretofore existed in such mechanisms.

My invention consists of the parts and the constructions and combinations of parts which I will hereinafter describe and claim, reference being had to the accompanying drawing in which,—the figure is a longitudinal vertical section of a reciprocating engine embodying my invention.

20 My invention relates more particularly to that class of reciprocating engines employed in conjunction with rock drills, and the object is to produce a valve motion to actuate the engine piston and rock drill in such a manner as to eliminate defects which have heretofore existed in such mechanisms.

In the accompanying drawing, A is the cylinder having the piston B adapted to reciprocate therein, and the piston rod extending through the end of the cylinder to connect with the part to be reciprocated. 30 The ends of the piston fit the cylinder, forming fluid-tight joints therewith, and the central or body portion of the piston is turned down smaller than the cylinder diameter and provided with inclined shoulders between this body and the ends. A rocker arm 6 in the form of a circular segment is slidable in a machined groove which forms a guide for it, and the ends of this rocker arm are impinged against by the inclines of the piston as the latter is alternately reciprocated in the cylinder. Rods 5 are connected with the slidable 35 segment 6 at their inner ends, and the outer ends are connected with valves 2. These valves are cylindrical and slidable within cylindrical sleeves or seats 3 which are located as near the ends of the cylinder as possible to reduce the loss of the elastic medium which is transmitted through the valves to reciprocate the piston. The valve seats or sleeves are screw-threaded upon the outside, and are turnable in corresponding screw-threads in the seats in which the sleeves fit so that the valves and sleeves may be inserted or removed by removing the caps or plugs 4 which close the 45 end of the valve chamber in line with the valves. The cylindrical sleeves or seats within which the valves reciprocate, are supported as shown, in such a manner that the elastic medium which is transmitted 50 through the valves to actuate the piston, may circu-

late entirely around the sleeves, and thus have easy transmission through the sleeves and the valve passages to and from the cylinder. Air or other elastic medium of pressure, occupies the central space of the valve chamber, and the exhaust passages from each 60 end connect with a central exhaust passage as shown, so that the valves by reason of their connection with the slidable rocker 6 are reciprocated so as to alternately admit the propelling medium under pressure through the cylindrical valve seat, and through the 65 interior passage of the valve to one end of the cylinder, while at the opposite end the valve has been retracted so as to allow free escape of the medium through the valve seat exterior to the ends of the valve and thence 70 through the exhaust port. It will be seen in this construction that the air or other elastic medium under pressure, acts equally in each direction against the inner ends of the valves, thus placing them in perfect balance, and this balance is not substantially disturbed during the reciprocation of the valves, inasmuch as the passage of the propelling medium is transversely through the valve openings.

The sleeves or bushings within which the valves reciprocate are adjustable forward or back to regulate the amount of opening that the ports shall give, because when the rock drill is in an elevated position, the weight of the drill is an element which makes the valve adjustment an entirely different matter than that of an ordinary engine where the weight of the reciprocating parts does not affect the position of the valve ports. 85

In an ordinary engine, the valves are set the same at each end of the movement, while in the rock drill, the amount of opening may vary with reference to the position of the piston. The cylindrical sleeves also serve to prevent the wrist pins of the connecting rods 90 from slipping out endwise.

Having thus described my invention, what I claim as new and desire to secure by Letters Patent is,—

1. In an engine of the character described, a valve chamber parallel with the cylinder and having an inner fluid pressure chamber and an outer exhaust chamber, pairs of screw-threaded flanges at each end of the inner chamber with annular channels between each pair of flanges, cylindrical screw-threaded longitudinally and independently adjustable casings, fitting the threaded flanges and having ports registering with the pressure chamber and with the annular channels, elongated ports from said channels to the ends of the cylinder, valves fitting and slidable within the casings, and having reduced waists, through which communication is alternately made between the pressure chamber and the cylinder through the casing ports, and between the cylinder and the exhaust chamber through the annular channels. 95

2. In an engine, a cylinder having a reciprocating piston, and an elongated port at each end, a fluid pressure chamber with circular interior channels at each end registering with the cylinder ports, sleeves or casings fitted within the channel flanges, and extending into the pressure chamber, circumferential ports of less lengths than 100 105 110

the first named ports connecting with said chamber, and with the channels, and piston headed valves movable in unison to alternately and oppositely connect the cylinder ports with the pressure chamber, and with an exhaust 5 chamber.

3. In an engine, a cylinder, an elongated port at each end and a reciprocating piston, a fluid pressure chamber with circular interior channels at opposite ends, registering with the cylinder ports, casings or sleeves adjustable 10 longitudinally with relation to the channels, and having ports communicating with the pressure chamber and the

channels respectively, and piston headed valves, reciprocated in unison with the movements of the engine piston to alternately connect the interior of the casing and the cylinder, with the pressure chamber and with an exhaust 15 chamber.

In testimony whereof I have hereunto set my hand in presence of two subscribing witnesses.

EDWARD A. RIX.
